UNITED STATES PATENT OFFICE.

JOHN WILCOX, OF PHILADELPHIA, PENNSYLVANIA.

METALLIC PEN.

Specification of Letters Patent No. 15,992, dated October 28, 1856.

To all whom it may concern:

Be it known that I, JOHN WILCOX, of the city and county of Philadelphia, and State of Pennsylvania, have invented a new and 5 useful Improvement in Metallic Pens; and I do hereby declare that the following is a full, clear, and exact description of the construction and operation of the same, reference being had to the annexed drawing, forming part of this specification, in 10 which—

Figure 1 is a top view of pen and holding device; Fig. 2 is a side view of same; Fig. 3 is a section on $b' c'$; Fig. 4 is a longitudinal section of pen and holder; Fig. 5 is 15 a section on $a' a''$.

Similar characters of reference in the several figures denote the same part.

The nature of my invention consists in 20 the combination of a double pointed pen, with the mechanism by which it is connected with the holder, so as to have either point, at will, brought into position for writing.

In the drawing a represents the pen, 25 pointed at both ends. It is held at its middle by the flanges e of the plate f , as

shown in Fig. 5. This plate f is attached to the slide piece m by a rivet r , so as to turn upon the slide piece, when desired. This slide piece m , is movable within the 30 ordinary slide n of the holder H , as shown in Fig. 4. The point of the pen, not to be used, is inserted in the opening o of slide n .

This construction admits of the formation of two pens on a single piece of metal; 35 either of which may be brought into service at will; the other being securely held without injury to itself.

I claim as new and of my own invention, The double pointed pen, in combination 40 with the flanged swivel plate f , and slide piece m , constructed, arranged and operating, substantially as, and for the purposes set forth.

In testimony whereof, I have hereunto 45 signed my name before two subscribing witnesses.

JNO. WILCOX.
